UNITED STATES PATENT OFFICE.

PHILIP W. MACKENZIE, OF NEW YORK, N. Y.

APPARATUS FOR PRODUCING GAS.

SPECIFICATION forming part of Letters Patent No. 334,447, dated January 19, 1886.

Application filed September 29, 1884. Serial No 144,291. (No model.)

To all whom it may concern:

Be it known that I, PHILIP W. MACKENZIE, of the city and county of New York, in the State of New York, have invented a new and useful Improvement in Apparatus for Producing Gas for Illuminating and Heating Purposes, of which the following is a specification.

This invention is applicable to apparatus in which carbonic oxide or a mixture of carbonic oxide and hydrogen is generated, either for use as a fuel-gas or to be enriched by the addition to it while it is in a highly-heated state, of a vapor or gas obtained by the distillation of liquid hydrocarbon.

The invention relates to those furnaces or generators which are severally provided with a central outlet-pipe for gas, and a number of feeding-throats or openings communicating with the top of the furnace at different points around the wall of the furnace.

The invention consists in the combination, with an upright furnace, of a gas-outlet pipe leading from the top of the furnace at the center thereof, two or more feeding-throats converging from their upper ends downward and communicating with the top of the furnace at different points around the wall of the furnace, hoppers for coal surmounting the feeding-throats and having their outer sides or walls inward of the outer walls of the throats, covers for the hoppers, and valves hinged below the hoppers and beyond or outward of the outer walls of the hoppers, whereby provision is afforded for so opening the valves as to leave a clear opening from the hoppers into the feeding-throats. When the hoppers are to be charged with coal, their covers are removed and the valves between the hoppers and feeding-throats are closed; but after charging the hoppers their covers are replaced and the said valves are opened.

Figure 1 in the drawings represents a central vertical section of a furnace or generator with my improvement. Fig. 2 is a plan of the same.

Similar letters of reference indicate corresponding parts in both figures.

The furnace or generator represented is, except as to the arrangement of the gas-outlet pipe and the means of providing for supplying it with the fuel or gas-producing material, in some particulars like the furnace or gen-

erator represented in my Patent No. 201,808, dated March 26, 1878, and in some particulars like that described in my Patents Nos. 246,962 and 246,963, dated September 13, 1881—that is to say, it consists of the upright fuel-receptacle A, having a grate, C, at the bottom, and an air-tight ash-pit, D, below, and surrounded by a jacket, B, within which there is formed a circuitous or interrupted flue or passage, *a a*, by means of flanges *b b*, attached to the outside of the receptacle A, the said flue or passage receiving air and steam through an injector, *c*; but so far the said furnace or generator constitutes no part of the present invention, which relates only to the means of feeding fuel and the arrangement of the same with reference to the gas-outlet, which I will now proceed to describe. The gas-outlet pipe E is arranged at the center of the top of the furnace or generator, and around or at the side of the mouth or entrance *e* of this pipe there are provided at equal distances apart and near the outer wall of the receptacle the fuel-openings *ff*, of which I prefer that there should be at least three, but of which in the furnace represented there are four. These fuel-openings enter the very top of the furnace-chamber A. Each of these fuel-openings *f* is provided with a long taper throat-piece, *G*, extending downward to it, and on the top of each of these throat pieces is a capacious hopper, *H*. The feeding-throats *G* converge from their upper ends downward; and hence, while their lower ends are brought sufficiently close together to enter the top of the furnace, their upper ends are so spread that large hoppers may be arranged upon them. Each hopper is fitted at its mouth with a gas-tight cover, *K*, and between each hopper and its throat-piece there is applied an inwardly-closing gas-tight valve, *I*, which is so attached to a rock-shaft, *g*, passing through one side of the throat-piece, that it may be opened and closed by a lever, *J*, secured to the said rock-shaft outside of the throat-piece and hopper. The upper ends of the feeding-throats are wider than the outlets of the hoppers, and the outer sides or walls of the hoppers are inward of or nearer the center of the furnace than the outer walls of the feeding-throats. The valves *I* are hinged below the hoppers and outward of or beyond the outer walls of the hoppers, and

consequently when the valves are opened they are approximately coincident with the outer walls of the hoppers and afford a clear outlet from the hoppers into the feeding-throats, so that there shall be no danger of the hopper-outlets becoming clogged with coal.

When this furnace is to be used for generating gas to be afterward enriched by the addition of a gas or vapor obtained by the distillation of a liquid hydrocarbon, the last-named gas or vapor may be introduced to the first-named gas in any suitable manner, but preferably as near as possible to the mouth *e* of the gas-outlet pipe *E*.

15 In Fig. 1 I have represented the pipe *h*, which supplies the enriching gas or vapor, as bringing it to a jacket, *i*, surrounding the pipe *E* close to the furnace and communicating with said pipe through numerous small orifices, *j j*.

To start the operation of the apparatus, the ash-pit door *L* is opened, and so are the valves *I* and covers *K*, and the kindling material and the coal are introduced through the throats *G*. 25 The furnace is gradually filled up with fuel by filling the hoppers while their valves *I* are closed, and afterward closing their covers *K* and opening the valves *I*. When the furnace is quite full of fuel and the latter is well ignited, 30 the ash-pit door *L* is closed, and steam and air is introduced by the injector *c*. The steam and air circulates together downward through the jacket *a* and through the openings *ll* in the bottom of the latter to the ash-pit, whence 35 they pass into the heated coal in the furnace, wherein they are decomposed and form with the gases of the coal a mixture of carbonic oxide and hydrogen, which passes to the pipe *E*, wherein, if it is to be enriched for illuminating purposes, it meets the gas or vapor supplied for such enrichment.

The furnace is kept filled up with coal to the top, and the throats *G* and hoppers *H* have also a quantity of fuel kept in them for the 45 automatically-continuous supply of the furnace, which is to be kept up in the following manner: The covers *K* are only required to be opened for filling their respective hoppers; but the valves *I* are always to be open, except 50 at the time of filling their respective hoppers, which is to be done whenever the coal gets so low in the throat *G* as to permit its valve to work clear of it. This is about the condition shown in the throat *G* at the right side of Fig. 55 1. The valve is then closed and the hopper-cover opened, and the hopper is filled with coal and its cover is again closed. The valve *I* is then opened, as shown at the left-hand side of Fig. 1, and the coal then runs from the 60 hopper into the throat and fills the latter, the hopper remaining partly full and continuing for a time to keep the throat full, as the latter is continually and automatically discharging itself into and feeding the furnace. This automatic feeding operation will continue so long as there is coal in the throat. So soon as the 65 coal in the throat gets low enough to permit

the closing of its valve, which is ascertained by trying the valve with its lever *J* from time to time, the valve is closed, as shown at the right hand of Fig. 1, the hopper cover is taken off and the hopper filled with coal, after which the hopper-cover is closed and the valve opened again. In this way the furnace is kept automatically filled to the top; but the mouths *f* of the feeding-throats being arranged around the mouth *e* of the central gas outlet, there is left in the center of the top of the fuel under the said outlet a space of inverted conical or funnel-like form, into which the gas from the 80 coal is concentrated toward the said outlet *e*.

By thus providing for the automatically-continuous feeding of the coal to the furnace or generator, the furnace operates with very little variation, and the gas always issues at 85 the outlet *e* at so high a temperature that it will produce the destructive distillation of any hydrocarbon vapor introduced into it near the said outlet for its enrichment.

This improvement remedies a defect which exists in all gas-generating apparatus of this 90 class into which the coal is fed in charges at intervals of time, the fresh fuel so introduced when the burning or highly-heated fuel previously remaining in the furnace is very low, 95 as is sometimes the case, so reducing the temperature of the furnace for a considerable time that the gas produced in the furnace during such time is not only itself of inferior quality, but leaves the furnace at so low a temperature as to render it incapable of producing the 100 destructive distillation of the hydrocarbon vapors introduced into it for its enrichment, and the consequence is that the said vapors condense and leave a very inferior gas.

The grate employed in this furnace may be of any suitable kind. That which is represented in the drawings is not herein particularly described, as it is intended to be the subject of another application for Letters Patent.

By two or more feeding throats or passages, arranged as described, I deliver coal at different points around the wall of the generator, and the coarser coal tends toward the center of the generator. The steam, when admitted 115 to the ash-pit, would naturally tend to pass upward along the wall of the generator; but when the coal is fed around the wall of the generator the finer coal remains around the wall while the coarser rolls to the center, and consequently the center and shallower mass of coarser coal offers about the same resistance to the passage of steam as the deeper mass of finer coal lying against the wall of the generator.

I am aware that it is not new to provide in the top of a gas-generating furnace a central gas-outlet pipe and a number of feeding openings or throats at different points around the said gas-outlet pipe; and I am also aware that a furnace has been provided with a single feeding-throat surmounted by a single hopper. I do not therefore claim such features, broadly, as of my invention.

It is desirable that the hoppers and feeding-throats shall be as large as possible, so as to hold a good supply of coal, and to enable the coal to gravitate downward through the outlets of the hopper without clogging, and the furnaces of this class are seldom of very large diameter. By making the feeding-throats so that they converge downward from their upper ends, and arranging the hoppers as far inward as possible on the tops of the feeding-throats, with their outer walls inward of the outer walls of the throats, I am enabled to hinge the valves I outward of or beyond the outer walls of the hoppers, so that when opened downward they will be substantially coincident with the outer walls of the hoppers, and hence there will be no liability of the hopper-outlets becoming clogged.

What I claim as my invention, and desire to secure by Letters Patent, is -

The combination, with an upright furnace,

A, for producing gas, of a gas-outlet pipe, E, leading from the top of the furnace at the center thereof, and two or more feeding-throats, G, converging downward from their upper ends and communicating with the top of the furnace around the wall of the furnace, hoppers H, surmounting the converging feeding-throats G, and having their outer sides inward of the outer walls of the throats, covers K for said hoppers, and valves I, hinged below the hoppers and beyond or outward of the outer sides or walls of the hoppers, whereby provision is afforded for so opening them downward as to leave a clear opening from the hoppers into the feeding-throats, substantially as herein described.

P. W. MACKENZIE.
